UNITED STATES PATENT OFFICE.

WILLIAM J. GOODRICH, OF DETROIT, MICHIGAN, ASSIGNOR OF ONE-THIRD TO HARRY HELFMAN AND ONE-THIRD TO SIDNEY M. SCHOTT, BOTH OF DETROIT, MICHIGAN.

ADJUSTABLE ANCHORAGE FOR MOTORS.

1,284,313.

Specification of Letters Patent. Patented Nov. 12, 1918.

Application filed April 19, 1918. Serial No. 229,584.

To all whom it may concern:

Be it known that I, WILLIAM J. GOODRICH, a citizen of the United States of America, residing at Detroit, in the county of Wayne 5 and State of Michigan, have invented certain new and useful Improvements in Adjustable Anchorage for Motors, of which the following is a specification, reference being had therein to the accompanying 10 drawings.

The invention relates to an adjustable anchorage for motors in which the motor is adapted for use particularly on lines equipped with magnetic clutches, which require 15 a very fine and accurate adjustment in order to insure perfect operation. One object of the invention is to obtain a construction permitting of the adjustment of the motor upon the bed plate in all directions so that the motor shaft may be accurately 20 alined with the machine to be driven. Another object is to obtain means for moving the motor sidewise in either direction and to rotate the motor and also to guide the motor 25 when being moved in a transverse direction. Further objects reside in the novel arrangements and combinations of parts as more fully hereinafter set forth.

In the drawings:

30 Figure 1 is a top plan view of the bed plate, with the motor base removed, to which my invention is applied;

Fig. 2 is a side elevation partly in section, with a portion of the motor base 35 shown;

Fig. 3 is a cross section on the line 3—3 of Fig. 1.

A is the bed plate which is fixedly secured in the concrete foundation A' by means of 40 the bolts A². The bed plate is provided at opposite ends with the recesses B in its upper surface within which are located the converging guides B' having the inner bearing surfaces B². These guides are fixedly secured 45 to the bed plate by suitable securing means, such as the screw bolts B³. C, C', C² and C³ are wedges arranged in pairs and slidably engaging said bearing surfaces B². Each of the pair of wedges is spaced from 50 the other to provide the parallel bearing faces D. E are anchor bolts at the corners of the bed plate A engaging slotted bearings E' therein and adapted to engage the base F of the motor. The base F is provided 55 with the alined grooves F' in its bottom sur-

face which are engaged by the keys G engaging the parallel bearing faces D of the wedges.

For adjusting the wedges C, C', C² and C³, the screw threaded studs H are provided 60 secured to the guides B' and passing through the lugs I upon the wedges. Nuts J and J' upon opposite sides of the lugs I and threadedly engaging the studs H are provided for respectively moving the wedges outwardly 65 and inwardly relative to the bed plate.

In operation, the motor base F can be moved transversely of the bed plate A in either direction by loosening the anchor bolts E and by adjusting the wedges. To 70 move the motor base in the direction marked by the arrow in Fig. 1, the wedges C and C³ are moved outwardly and the wedges C' and C² are moved inwardly thereby moving the same transversely of the bed plate A due 75 to the inclined guides B' and correspondingly moving the motor base F through the keys G. To move the motor base in the opposite direction, the wedges C' and C² are moved outwardly relative to the bed 80 plate A and the wedges C and C³ are moved inwardly relative to the bed plate thereby moving the keys G and the motor base in the desired direction. If it is desired to slightly 85 rotate the motor base in a clock-wise direction, this can be done by moving the wedges C' and C³ outwardly relative to the bed plate A and by moving the wedges C and C² inwardly relative to the bed plate. To move the motor base longitudinally, the anchor 90 bolts E are loosened and the motor base is adjusted in the desired direction, the keys G guiding the motor base during this movement.

From the above description it will be 95 readily seen that I have provided an anchorage for motors which permits of adjustment of the latter to a limited extent in all directions. Furthermore, the means for moving the motor base transversely of the 100 bed plate is positive and minutely accurate and furthermore guides the base when being moved longitudinally.

What I claim as my invention, is:

1. The combination with a bed plate having bearing surfaces at opposite ends, and pairs of spaced coöperating wedges engaging said bearing surfaces, of a movable member mounted upon said bed plate, means for actuating said movable member from said 110

wedges, said means engaging the space between each pair of wedges, and means for actuating said wedges.

2. The combination with a bed plate having grooved bearings at opposite ends, of a movable member mounted upon said bed plate, a pair of coöperating wedges slidably engaging each of said grooved bearings and having spaced parallel bearing faces, members 10 engaging said movable member and the bearing faces upon said wedges, and means for actuating said wedges.

3. The combination with a bed plate having converging bearing surfaces at opposite 15 ends, of a movable motor base mounted upon said bed plate and having alined grooves at opposite ends, pairs of coöperating wedges slidably engaging said bearing surfaces, said wedges having spaced parallel bearing faces, 20 keys engaging said bearing faces and said grooves in the motor base, and threaded members secured to said bed plate and engaging said wedges for actuating the latter.

4. The combination with a bed plate hav-

ing converging grooved bearings at opposite 25 ends, of a movable motor base mounted upon said bed plate and having alined grooves at opposite ends, a pair of coöperating wedges slidably engaging each of said grooved bearings, said wedges having spaced parallel 30 bearing faces, keys engaging said bearing faces and said grooves in the motor base, threaded members secured to said bed plate and engaging said wedges for actuating the latter, and connections between said motor base and bed plate permitting of movement longitudinally of said keys, said keys guiding said motor base during said movement.

5. The combination with a bed plate, of a movable member mounted thereon, and means for adjusting said movable member in opposite directions and for rotating the same, said means also forming the guide for said movable member when being adjusted in a direction transverse of the first-mentioned directions.

In testimony whereof I affix my signature.

WILLIAM J. GOODRICH.
